DOLL

Mary W. Peters, Boulder, Colo.

Application August 6, 1953, Serial No. 26,335

Term of patent 14 years

(Cl. D34—2)

To all whom it may concern:

Be it known that I, Mary W. Peters, a citizen of the United States, residing at Boulder, State of Colorado, have invented a new, original, and ornamental Design for a Doll, of which the following is a specification, reference being had to the accompanying drawing, forming a part hereof.

The side opposite from that shown in Figure 2 and which has not been illustrated is the same as that shown in Figure 2 but reversed.

I claim:

The ornamental design for a doll, as shown.
MARY W. PETERS.
